UNITED STATES PATENT OFFICE.

JOHN F. WILLEY AND ELMER W. WATSON, OF VERSAILLES, ILLINOIS.

SAD-IRON.

No. 853,138.

Specification of Letters Patent.

Patented May 7, 1907.

Application filed March 14, 1906. Serial No. 305,988.

To all whom it may concern:

Be it known that we, JOHN F. WILLEY and ELMER W. WATSON, citizens of the United States, and residents of Versailles, in the 5 county of Brown and State of Illinois, have invented a new and Improved Sad-Iron, of which the following is a full, clear, and exact description.

This invention is an improvement in sad 10 irons and has for an object, among others, to provide a comparatively cheap, simple and effective self-heating iron, presenting a neat appearance without any overhanging or cumbersome parts likely to interfere with its 15 proper use. This object is accomplished by our invention, one embodiment of which is hereinafter disclosed.

Reference is to be had to the accompanying drawings forming a part of this specification, in which similar characters of reference 20 indicate corresponding parts in all the figures.

Figure 1 is a vertical, central, longitudinal section of our improved iron on the line 1—1 25 of Fig. 2, and Fig. 2 is a section on the line 2—2 of Fig. 1.

In the drawings, 1 indicates the body portion 30 of the iron, and, as shown, consists of a single casting containing a fuel tank and a burner, and provided with cooling means, and having formed at the top thereof a handle 2. This is an important feature of construction, since it obviates the necessity of suspending these necessary elements from 35 various parts of the supporting structure. The body of the iron is composed of a base 3, a top 4, sides 5, ends 6 and 6^a and partitions 7 and 8 dividing the interior of the structure into three substantially equal compartments. 40 On the base 3 at each end thereof are supports 9, having forked upper ends for receiving the ends of a tubular burner 10, having apertures in its under side for the purpose of projecting a series of small flames toward the 45 base 3.

The compartment between the partitions 7 and 8 is provided with an asbestos mat 7^a, resting on the partition 7 and held from slipping therefrom by a projecting toe 7^b, on said 50 partition. This compartment also contains large ventilating holes 11 at each side, for permitting a free circulation of air between the partitions and keeping this part of the body of the iron in a cool condition. The space 55 between the top 4 and partition 8 constitutes

a tank for containing fuel for the burner 10 in the lower compartment of the body, and has a filling plug 12 screwed or otherwise secured at some convenient point on the top 4.

The handle 2 has a bore 3^a, in which a piston head 13 can be reciprocated by means of a stem 14 formed with an eye 15 at its outer end, said stem passing through the center of a screw-threaded cylinder head 16, which forms a guiding means for the stem. The opposite cylinder head 17 is made integral with the handle and is connected to the top of the fuel tank by a pipe 18. Slidable on guides at each side of an opening in the end 6 extending from the compartment 5 to near the base 70 3, is a damper 19 having a handle 20 for sliding it on the guides and regulating the supply of air admitted to the burner. The opposite end of the burner chamber has at the top a hole 21 at each side (one of said openings being shown in Fig. 1) for expelling the products of combustion. In the wall 6, near the bottom of the tank, is screwed a pipe 22 connected to a cut-off valve 23, and leading therefrom to the burner chamber over and 75 near the top of the burner, said pipe forming a U, with one end connected to the burner at its under side near the point where the pipe enters the burner chamber.

In the operation of the iron, the tank is 80 filled with the liquid fuel through the filling plug 12, to about the height as shown in Fig. 1, leaving a space above the fuel in which air can be compressed by the piston 13. When sufficient pressure is attained for proper feeding, the valve 23 is opened and the burner lighted in the usual manner. The numerous flames directed to the base by the burner will heat this portion very hot, the temperature of which can be regulated by the valve 23. 85 The partition 7 will be much cooler than other parts of the burner chamber and will have the major portion of its heat confined by the mat 7^a, thereby, in conjunction with the ventilating holes 11, lowering the temperature of the air chamber and keeping the fuel above in the tank in a cool and safe condition. 90

Having thus described our invention we claim as new and desire to secure by Letters 95 Patent:

1. In a sad iron, the combination of a casting, a handle fixed to the top of the casing, a piston in the handle, partitions in the casting dividing it into compartments, a burner 100

in the lower compartment, the upper compartment forming a fuel tank, and the central compartment forming a cooling chamber, a pipe connecting the handle with the tank, 5 and a pipe connecting the tank with the burner.

2. In a sad iron, the combination of a casting, a handle fixed at the top of the casing, partitions in the casing dividing it into compartments, a burner in the lower compartment, the upper compartment forming a fuel tank and the central compartment forming a cooling chamber, a pipe connecting the handle with the tank, and a pipe connecting the 15 tank with the burner.

3. In a sad iron, the combination of a casting, a handle fixed at the top of the casing, partitions in the casing dividing it into compartments, a burner in the lower compartment, the upper compartment forming a fuel tank and the central compartment forming a cooling chamber, a pipe connecting the handle with the tank, a pipe connecting the tank with the burner, and means for forcing air 20 into the tank.

4. A sad iron comprising a hollow body, partitions in said body dividing it into compartments, a burner in the lower compartment, the upper compartment forming a fuel tank and the central compartment forming an air chamber having ventilating holes, and a feed pipe leading from the tank to the burner.

5. A sad iron comprising a hollow body, a 35 hollow handle fixed at the top of said body, partitions in said body dividing it into compartments, a burner in the lower compartment, the upper compartment forming a fuel tank and the central compartment forming an air chamber having ventilating holes, a piston in the handle, adapted to force air into 40

the tank, and a feed pipe leading from the tank to the burner.

6. A sad iron comprising a hollow body, partitions in the body dividing it into compartments, an opening at the back end of 45 said body, a burner in the lower compartment, the upper compartment forming a fuel tank and the central compartment forming a cooling chamber having air holes, and a damper slideable in the opening at the back of the body of the iron, to regulate the admission of air to the burner.

7. A sad iron comprising a hollow body, partitions in said body dividing it into three 55 compartments, forming respectively a burner chamber, an air chamber and a fuel tank, a hollow handle at the top of said body, containing a piston for forcing air into the tank, an opening at the back end of the body, a 60 damper slideable in the opening, and a fuel pipe having a regulating valve connecting the tank and the burner.

8. In a sad iron, the combination of a casting of substantially uniform, horizontal section throughout, a handle fixed to the top of the casing, a piston in the handle, partitions in the casing dividing it into compartments, a burner in the lower compartment, the upper compartment forming a fuel tank and the central compartment forming a cooling chamber, means for connecting the handle 65 with the tank, and means connecting the tank with the burner.

In testimony whereof we have signed our 75 names to this specification in the presence of two subscribing witnesses.

JOHN F. WILLEY.
ELMER W. WATSON.
